(57) **CLAIM**

The ornamental design for a combination parcel locker and vehicle battery charger, as shown and described.

DESCRIPTION

FIG. 1. is a front view of a combination parcel locker and vehicle battery charger according to the present invention.

FIG. 2 is a left side view thereof; and,

FIG. 3 is a front perspective view thereof.

The broken lines in the drawings depict portions of the combination parcel locker and vehicle batter charger that form no part of the claimed design.

The logo comprising an image of the sun and the wording INPOST is a registered trademark of Inpost Paczkomaty. z o.o. and InPost S.A. and forms no part of the claimed design.

1 Claim, 3 Drawing Sheets
